POURING SHEET

George W. Watrous, Battle Creek, Mich., assignor
to The Duplex Printing Press Company, Battle
Creek, Mich.

Application August 10, 1940, Serial No. 352,141

2 Claims. (Cl. 22—2)

This invention relates to pouring sheets for use in hand operated casting boxes for making tubular plates. It has for its objects:

First, to provide a new and improved pouring sheet of the class described.

Second, to provide such a sheet which is reinforced in such a way as to tend to prevent injury thereof without interfering with the practical use thereof in a casting box, even though very light weight metal is used in forming the sheet so that it will not have sufficient mass to chill the printing edge of the plate.

Third, to provide such a sheet with a reinforcing and stiffening member thereon which serves as a stop to limit movement into the casting box.

Other objects and advantages pertaining to details and economies of construction and operation will appear from the description to follow. The invention is defined in the claims. A preferred embodiment of my invention is illustrated in the accompanying drawing, in which:

Figure 1 is a side view of a casting box with my improved sheet in position therein.

Fig. 2 is a detail partial sectional view taken on the line 2—2 of Fig. 3.

Fig. 3 is a detail sectional view taken on the line 3—3 of Figs. 1 and 2.

Fig. 4 is a perspective view of my improved pouring sheet.

My improved pouring sheet 1 is specially designed for use in a casting box 2 for casting tubular plates for use on printing presses such as newspaper presses. Such a casting box consists of a suitable base 3 on which a stationary drag 4 is mounted. A hinged cope 5 is mounted to swing to close a semi-cylindrical opening in the face of the drag and is also provided with such a semi-cylindrical opening in its face to form a cylindrical casting space 6. Above the cylindrical opening 6 in such casting boxes, a fixed spout 7 is provided for the type metal.

My improved pouring sheet 1 consists of a thin sheet 8 of spring steel formed into a curve slightly larger than the curve of the inside of the cylindrical opening 6 of the casting box, so that when the sheet is inserted in the top of the cylindrical opening 6, it will resiliently hug the walls thereof. The circumferential dimension of the sheet when it is in position is substantially the same as the circumferential dimension of the cylindrical opening 6 in the casting box. The only difference is represented by the width of the mat bar 9.

The pouring sheet extends downwardly into the cylindrical opening 6 so that its lower edge

10 overlaps the upper edge of the matrix 10 as shown in Fig. 2, and it is essential that the sheet metal forming the pouring sheet be sufficiently thin so that its mass will be sufficiently small to prevent excess chilling of the printing edge of the plate. If such thin sheet metal is used, the sheet is apt to become damaged and to reinforce the sheet I provide a spring metal band 11 extending circumferentially of the sheet and of a length to substantially surround the sheet. The ends 12 of the band are bent outwardly away from the sheet as is best shown in Figs. 3 and 4, so that the band and particularly its ends may serve as stops to limit movement of the pouring sheet into the top 15 of the casting box as is well shown in Fig. 2. The band 11 is preferably welded to the sheet, although it might be fastened in other ways.

In order to insert the pouring sheet, it is necessary to spread the edges 13 thereof somewhat in order to permit the pouring sheet to pass the spout 7 and the resiliency of the sheet must be such that it is easy to spread the sheet. The resiliency of the band 11 in place, added to the resiliency of the sheet, must not be too great to permit this.

I have found that the provision of the reinforcing band makes it practical to use very thin sheet metal in forming the sheet, since the band tends to stiffen the sheet and to resist deformation thereof. The band may be applied at a minimum of cost and with the ends of the band bent as shown, it is not necessary to make use of any additional stops.

The terms and expressions which have been 35 herein employed are used as terms of description and not of limitation. There is no intention in the use of such terms and expressions of excluding any equivalents of the features shown and described. It is recognized that various modifications 40 are possible within the scope of the invention claimed.

Having thus described my invention what I claim as new and desire to secure by Letters Patent is:

- 45 1. A pouring sheet for use with casting boxes for making tubular plates comprising a thin sheet of spring metal formed on a curve slightly larger than the curve of the inside of the box and of a length to extend into the top of the box far enough to cover the upper edge of the matrix and to extend above the top of the box and sufficiently flexible to permit a user to spread it, and a band of metal extending circumferentially of said sheet and fastened to the outer surface 50 thereof to stiffen and reinforce said sheet and

leaving the sheet sufficiently flexible to be spread by the user and substantially surrounding the sheet at the top of the box when the sheet is in place.

2. A pouring sheet for use with casting boxes for making tubular plates comprising a thin sheet of spring metal formed on a curve slightly larger than the curve of the inside of the box and of a length to extend into the top of the box far enough to cover the upper edge of the matrix and to extend above the top of the box, and a

5 band of metal extending circumferentially of said sheet and fastened to the outer surface thereof to stiffen and reinforce said sheet and having its ends extending substantially to the meeting edges of said sheet and being curved away from said sheet to serve as stops to engage the top of the casting box to limit movement of the sheet into the casting box, said band substantially surrounding the sheet at the top of the box when the sheet is in place.

GEORGE W. WATROUS.
